Patented Aug. 10, 1915.

UNITED STATES PATENT OFFICE.

THOMAS D. FINIZIO, OF NEW YORK, N. Y., ASSIGNOR TO KURZ ELECTRICAL COMPANY, INC., OF NEW YORK, N. Y., A CORPORATION OF NEW YORK.

LAMP-SHADE.

1,149,817.

Specification of Letters Patent. Patented Aug. 10, 1915.

Application filed May 10, 1915. Serial No. 27,281.

To all whom it may concern:

Be it known that I, THOMAS D. FINIZIO, a subject of the King of Italy, residing at New York city, Bronx county, State of New York, have invented certain new and useful 5 Improvements in Lamp-Shades, of which the following is a full, clear, and exact description.

This invention relates to an improvement 10 in lamp-shades, but more particularly to shades for electric lamps.

The object of the invention is to provide a shade having a pivotal frictionally resisted connection with the bracket for securing the shade to the lamp, the said bracket being arranged to releasably grip the metal portion of the lamp.

A further object is to provide a lamp-shade embodying the features above mentioned that can be cheaply manufactured and easily applied.

I will now proceed to describe my invention in detail, the essential features of which will be summarized in the appended claim, 25 reference being had to the accompanying drawing, forming part hereof; wherein—

Figure 1 is a side elevation of an ordinary electric-light bulb having my improved shade applied thereto, the said shade being 30 broken away to show the connection between the shade and clamp or supporting medium therefor. Fig. 2 is a detail view of my improved shade; Fig. 3 is a detail perspective view of one form of the gripping end of my 35 improved shade-clamp; and Fig. 4 is a similar view of another form of shade clamp.

In the drawing, an electric-lamp bulb is indicated by 1, while 2 indicates a common form of wall-socket therefor. My improved 40 shade consists of a hemispherical cup 3 secured to a bracket 4 preferably made out of a single strand of wire of any suitable resilient metal.

The bracket 4 consists of a resilient clamping portion 5 and resilient arms 6 which are pivotally connected to the shade 3 (in this instance) by rivets 7. The pivotal connection at 7 permits the shade 3 to be angularly adjusted, relatively to the axis of 45 the bulb 1, as shown by the dotted line 3^a in Fig. 2, in order that the direction of the rays of light can be changed to suit conditions. The resilient bracket 4 consists of a plurality of oppositely directed loops arranged 55 to form a jaw 8 (Fig. 3), the oppositely di-

rected loops referred to being indicated by the numerals 9 and 10, 9^a and 10^a. The member 11 of the clamp which forms one side of the loops 10 and 10^a is continuous and is of such a length as to extend substantially half way around the metal body portion 11 of a standard size lamp 1. The loops 9 and 9^a, which are curved to correspond with the curvature of the member or portion 11, extend toward each other, but 60 do not meet. By this construction the clamp portion 5 can be formed so as to firmly grip the body of the lamp, as its members, the loops referred to, will be yieldable. The arms 6 of the bracket 4 are yieldable and are, 65 when placed in the shade 3 for securement, pressed toward each other, or in other words, sprung into the shade 3. By means of this feature, the arms 6 will always tend to spring outwardly and press against the 70 shade 3, thereby providing a frictional contact which will prevent the shade from moving too freely, even though the riveted connection becomes slack.

Fig. 4 illustrates a bracket, the clamp 12 80 of which is made out of one piece of resilient flat metal, the arms 13 of said bracket being integral with the clamp portion. The arms 13 of this latter form of bracket are secured to the shade 1 in the same manner 85 as the arms 6 of the form illustrated in Fig. 1. As the engagement of the clamping portion of the bracket is wholly external and said portion conforms to the curvature of the lamp socket, or of any other cylindrical 90 part which may be substituted for the latter, it follows that there is no impediment to turning said bracket around the said socket without separation therefrom, thus carrying the lamp-shade around the axial line of 95 the socket and lamp. Also, the bracket and shade may be detached at will by the exertion of a little force in spreading apart the loops of the resilient clamping portion of 100 said bracket. The open loops 10, 10^a present much broader and more efficient frictional surface than would two bars in contact with each other.

Having now described my invention, what I claim and desire to secure by Letters Patent is:

In combination with a lamp shade and a cylindrical device below the same, a resilient bracket in one piece consisting of downwardly converging arms carrying said shade 110

on their upper ends and of a lower and middle clamping portion which is bent to correspond to the periphery of said cylindrical device, said clamping portion comprising a pair of open loops extending toward each other without touching, a lower pair of loops extending away from each other and a curved lower member 11 connecting said lower loops and partly composed of portions of them, the said clamping portion fitting resiliently on approximately one half of the periphery of said

cylindrical part and holding the shade detachably in position above said device, though also permitting the shade to be turned about the axial line of said cylindrical device.

Signed at New York city, N. Y. this 7 day of May, 1915.

THOMAS D. FINIZIO.
